UNITED STATES PATENT OFFICE.

CHARLES A. BRICKEL, OF NEILSONVILLE, QUEBEC, CANADA.

FIRE-ESCAPE.

1,136,931.

Specification of Letters Patent.

Patented Apr. 27, 1915.

Application filed April 21, 1914. Serial No. 833,557.

To all whom it may concern:

Be it known that I, CHARLES A. BRICKEL, a citizen of the United States, residing at Neilsonville, in the Province of Quebec and Dominion of Canada, have invented certain new and useful Improvements in Fire-Escapes, of which the following is a specification.

This invention relates to an improved fire escape mechanism in which the velocity of descent is determined by the person who is descending.

An object of the invention resides in an improved means which is associated with the escape in order to accurately rewind the cable on the drum after the person has descended, so that the convolutions will lie snugly in engagement with each other; a tensioning element being associated with the rewind means for holding the cable taut, to facilitate rewinding.

A further object of the invention is to provide an improved carrier for the person who is to descend, the latter in the present instance being made of leather straps which engage the body of the person descending, so as to positively prevent his or her equilibrium from being disturbed during descent.

A still further object of this invention is the provision of a suitable mechanism which can be readily associated with an article of furniture or the like in the room from which the person is desiring of escaping, without the use of tools, nails, screws or any other analogous instrumentalities.

Other objects as well as the nature, characteristic features and scope of my invention will be more readily understood from the following description taken in connection with the accompanying drawings and pointed out in the claims forming a part of this specification.

Referring to the drawings: Figure 1 is a side elevation of my improved fire-escape, illustrating the application thereof, Fig. 2 is an inverted side elevational view of my improved fire escape, showing to advantage the means for facilitating the rewinding of the cable on the drum, Fig. 3 is an end elevation of the same looking at the opposite end from that shown in Fig. 1, Fig. 4 is a cross sectional view taken on the line 4—4 of Fig. 2, Fig. 5 is a sectional view taken on the line 5—5 of Fig. 2, Fig. 6 is a perspective view of the crank for actuating the cable

drum in order to rewind the cable thereon, and likewise to regulate the velocity of descent of the person who is being carried by the cable, and Fig. 7 is a detailed enlarged sectional view of the means for facilitating the rewinding of the cable on the drum, the cable tensioning bolts being shown disengaged therefrom.

In the drawings wherein is shown the preferred form of this invention, a casing 5 is provided which in the present instance comprises a pair of disks 6, the latter being connected by bolts 7, one of said bolts being in engagement with a supporting member 8, 60 which in the present instance comprises a wire strand, the opposite ends of which are looped and the intermediate portion thereof depressed to provide a substantially U-shaped structure. A second disk 9 is slidably mounted on the rods 7, in proximity to one of the disks 6, for a purpose which will subsequently appear.

In order to illustrate the application of the invention, a bed 10 is shown in Fig. 1, 80 which is represented as being carried on an upper floor of the building 11, the bed being engaged by the hook 12, although the latter, if desired may be secured to any other object in the room which would be sufficient 85 to support the person descending. Revolvably mounted in the disks 6 and 9 is a shaft 13, which is fixedly engaged with a drum 14, the latter being revolvably mounted between the disk 9 and one of the disks 6 as 90 shown to advantage in Fig. 2, said drum having wound thereon a cable 15, the latter having one end thereof fixedly secured to the periphery of the drum and the opposite end extending beyond the casing 5 and into 95 engagement with the bed engaging hook 12. One end of the shaft 13 is squared, as indicated at 16 and is provided in each side thereof with a recess 16', said shaft 13 being squared in order to facilitate the actuation of the drum 14 for rewinding the cable 15 thereon and likewise regulate the velocity of descent when the crank hereinafter described is associated therewith.

In the furtherance of one of the above 105 specified objects in which the velocity of the descent of the person escaping is regulated by controlling the rotation of the drum 14, I have provided a plurality of studs 17 on one face of the disk 9, each of 110 which has encircled thereon a coil spring 18. In conjunction with this formation and

a disk 19, the disk 9 is held in engagement with one end of the drum 14, thereby yieldingly engaging said disk with the drum when pressure is exerted on the disk by the 5 set screws 20, the latter having engagement with one of the disks 6 and into engagement with the disk 19. It is obvious therefore that the disk 9 serves as a brake-shoe which is engaged with one end of the drum 10 14, thereby regulating the speed of rotation of the latter for performing the desired function. Bolts 21 are carried by the disk 9 and extend through the disks 6 and 19 in order to retain said latter disks in a predetermined position.

To those skilled in the art to which this invention appertains, it is well known that in rewinding the cable on the drum, that considerable difficulty is very often experienced by the cable becoming entangled during the rotation of the drum thereby preventing the accurate engagement of the cable with the drum to permit successive operations for carrying the occupant of the 25 building to the earth. In order to eliminate the undesirability of the cable being entangled while rewound, I have in the present instance provided an element generally designated 22 which comprises a pair of 30 parallel plates, each of which is provided with an opening in its opposite ends through which the rods 7 are engaged to permit sliding of the plate on said rods. Said plates have mounted therebetween studs 24 which 35 retain the plates in engagement, while a block 25 is mounted between the plates 23 in parallelism with the studs 24, the block being provided to facilitate sliding of the plates 23 on the rods 7 when the drum 14 is 40 rotated for rewinding the cable 15 thereon, since one end of the cable 15 passes through an opening 26 in the block 25, thereby imparting movement to the plates 23, so as to snugly engage the convolutions on the outer 45 periphery of the drum 14. During the rewinding of the cable on the drum, the same is held taut at all times in the opening 26 through the medium of a tensioning bolt 27, the latter having encircled around the shank 50 thereof a spring 28 in order to normally hold one end of the bolt 27 in the opening 26, said opening 26 communicating with an opening 29 in which the bolt 27 is slidably mounted, the latter provided with studs 30 55 which engage in corresponding slots in the block 25, in order to prevent the displacement of the bolt 27 while it is passing through its opening 29 with the cable 15 which passes through the opening 26.

60 The drum 14 is rotated through the medium of a crank 31 which is provided with a squared opening 32 complementary to the square shank 16 of the shaft 13, said crank being further provided with a plurality of 65 squared openings 33 which are adapted for

engagement with the various other nuts of the mechanism, in order to tighten or release the same as desired. This crank in the present instance comprises a metallic bar, one end of which is turned at right angles 70 to the body and rounded in order to facilitate the operation thereof, the free terminal of said right-angled portion being provided with one of the squared openings 33 in order to adapt the same for use on nuts of the 75 elongated type, or of the bolt heads. A set screw 31' is mounted in the head of the wrench and adapted to engage through the openings 32 and with the recesses 16' on the squared end 16 of the shaft 13, so as to positively prevent the disengagement of the crank from said squared shank 16, during descent, which is necessary at all times, during the transporting of the person from the building to the earth, that control of the 80 85 crank should be had, in order to regulate the velocity of descent. The carrier mechanism by which the person is conveyed from the building to the ground in the present instance comprises a plurality of interconnected straps 34 which are engaged by buckles 35, thereby permitting the adjustment of the straps, so as to fit persons of different sizes. The carrier member has mounted thereon a hook 36 by which it is 90 95 detachably engaged with a ring 37, the latter depending from the member 8, as advantageously illustrated in Fig. 1.

In operation, we will assume that the device is positioned as shown in Fig. 1. In this position, the screws 20 are normally retained in a predetermined position, so as to exert sufficient pressure against the end of the drum 14 to hold the latter from rotating while the person enters the carrier. To descend, the crank 31 is placed on the squared end 16 of the shaft 13 and the set-screw 31' engaged in one of the recesses 16' thereby positively preventing the accidental displacement of the crank as previously pointed out. The person desiring to descend then engages the strap 35 about his or her body and disengages the bolt 27 of the opening 26 allowing the cable 15 to freely pass in said opening 26, permitting the occupant of the carrier to descend at the desired rate of speed to the earth. When it is desired to rewind the cable 15 on the drum, pressure is exerted on the shaft 13 by the crank 31, during which operation, the disks 9 may be entirely disengaged from the drum 14 so as to allow for the free rotation of the latter, the cable being accurately wound on the drum 14 in view of the member 22, the function of which has been heretofore described. The cable after having been entirely wound on the drum being held in a taut position by engaging the bolt 27 through the opening 29 and into the opening 26 through which the cable passes. If a second party is desirous of descending, 120 125 130

- the entire mechanism is pulled up by the cable 15 to the room from which the previous party has escaped. The screws 20 are then tightened, thus leaving the drum 14 free to rotate by applying the crank 31 and engaging the bolt 27 through the opening 29 into engagement with the cable 15, so that the cable will be accurately rewound on the drum, when the crank is operated. The screws 20 are then released thereby locking the drum 14 and the bolt 27, then disengaged from the cable 15 and the mechanism is ready to transfer the next party to the earth.
- 15 It will be understood that the above description and accompanying drawings comprehend only the general and preferred embodiment of my invention and that various minor changes in details of construction, 20 proportion and arrangement of parts may be made within the scope of the appended claims and without sacrificing any of the advantages of my invention.

Having thus fully described my invention, 25 what I claim as new and desire to secure by Letters Patent is:

1. A fire escape including a frame, a drum revolvably mounted in said frame, a cable wound on said drum having one end 30 engaged therewith and the opposite end adapted to extend beyond the frame, means for regulating the speed of rotation of said

drum including a disk frictionally engaged with one end of the drum having studs extending from one face thereof, elastic elements associated with said studs, a disk engaged with said elastic elements for holding said first mentioned disk in yielding engagement with the drum, and set-screws extending through said frame and having engagement with said second mentioned disk for regulating the tension of said elastic elements for the purpose specified.

2. A fire escape including a frame, a drum revolvably mounted in the frame, a cable one end of which is in connection with said drum and the opposite end adapted for association with a person descending, a friction disk carried by the frame and engageable with one end of the drum, means directly connected with said disk and extending through said frame to hold said disk in a predetermined position for obtaining a minute adjustment of the disk, and means in yieldable connection with said disk, to permit slight movement of the latter when pressure is exerted on the cable for imparting movement to the drum.

In testimony whereof I affix my signature in presence of two witnesses.

CHARLES A. BRICKEL.
